Primary Examiner — Rachel A. Voorhies(74) *Attorney, Agent, or Firm* — Smith Baluch LLP(57) **CLAIM**

The ornamental design for a display screen portion with graphical user interface, as shown and described.

DESCRIPTION

FIG. 1 is a front view of a first embodiment of a display portion with graphical user interface showing our new design.

FIG. 2 is a front view of a second embodiment of a display portion with graphical user interface showing our new design; and,

FIG. 3 is a front view of a third embodiment of a display portion with graphical user interface showing our new design.

The outermost broken dot-dash perimeter in FIGS. 1-3 illustrates a display screen portion and forms no part of the claimed design. The dash-dot broken lines illustrate portions of the graphical user interface that form no part of the claimed design.

1 Claim, 3 Drawing Sheets(56)
